RECOIL SELECTOR MECHANISM FOR FIREARMS

Ralph D. Lambert, St. Louis, Mo.

Application July 22, 1955, Serial No. 523,768

12 Claims. (Cl. 89—198)

This invention relates to firearms, and in particular is concerned with a selector mechanism for regulating the recoil springs for semiautomatic pistols.

This improved recoil selector mechanism provides selected recoil spring forces which make possible the use of cartridges having different powder charges. Thus, a light recoil spring may be used in a .22 semiautomatic pistol for .22 shorts, and a heavier spring force may be used for .22 long rifles. It is to be understood that the invention, although described particularly for use with a .22 semiautomatic pistol, can be used with other pistols and other firearms.

By means of this invention the slide of a .22 semiautomatic pistol has been provided with a selector mechanism which can cut in or out of operation a single recoil spring. This selector mechanism when used with the standard recoil spring provides a means for increasing the spring load of the recoil when the selector mechanism is cut in to provide a total recoil spring force sufficient for a .22 long rifle. When a .22 short with less powder charge is utilized the selector mechanism is adjusted to the cut-out position in which only the one standard spring is in operation. Thus, there is offered in the selector mechanism of this invention a means for regulating the recoil spring force responsive to the high or low powder charge of a cartridge. This enhances the recoil operation in the semiautomatic firearm employed and greatly improves the efficiency of operation of the firearm.

Accordingly, it is an object of this invention to provide a semiautomatic firearm having a selector mechanism for adjusting the recoil spring load.

It is a further object of this invention to provide a selector mechanism for firearms adapted to receive cartridges of different explosive force in which the recoil spring force of the firearm can be regulated and selected, depending upon the explosive force of the cartridge.

Yet another object of this invention is to provide a selector mechanism for semiautomatic firearms to a cut-out and cut-in position for an auxiliary recoil spring used in addition to a full-time recoil spring.

Yet another object of this invention is to provide a semiautomatic firearm having a plurality of recoil springs in which a selector mechanism can be adjusted to a cut-out or cut-in position for regulating the operative effect of at least one of the recoil springs.

Still another object of this invention is to provide a selector mechanism for regulating the recoil course of a semiautomatic firearm in which standard parts and components are utilized to make possible a rugged and simple operating weapon.

Further objects of this invention will appear in the detailed description which follows and will be apparent to those skilled in the art.

Reference will now be had to the accompanying drawings showing a preferred embodiment of this invention.

For illustration the invention is shown in a .22 semiautomatic pistol, but it is to be understood that this is for

2

the purpose of example only and that the invention is not limited thereto.

In the drawings:

Figure 1 is a view in side elevation of a semiautomatic pistol;

Figure 2 is an enlarged top plan view showing the selector on the slide;

Figure 3 is a fragmentary enlarged view in elevation showing the slide in the recoil position;

10 Figure 4 is a view in section taken on the line 4—4 of Figure 1;

Figure 5 is a view in section taken on the line 5—5 of Figure 3;

15 Figure 6 is a fragmentary view showing an enlarged vertical section of the slide and breech portion of the pistol;

Figure 7 is an enlarged view in section taken on the line 7—7 of Figure 6 showing both recoil springs in the operative position and the slide in the forward position;

20 Figure 8 is a view similar to Figure 7 showing the slide in the recoil or rear position;

Figure 9 is a view similar to Figure 7 showing the slide in the forward position and with one spring in the cut-out position;

25 Figure 10 is a view in section taken on the line 10—10 of Figure 7 showing the construction of the slide;

Figure 11 is an enlarged view in section taken on the line 11—11 of Figure 3 showing the construction of the slide and the cartridge extractor;

30 Figure 12 is a view in front elevation showing the slide housing;

Figure 13 is a view in rear elevation showing the slide housing;

35 Figure 14 is an enlarged plan view of the selector switch;

Figure 15 is a view in side elevation of the selector switch; and

Figure 16 is a bottom plan view of the selector switch.

The pistol equipped with the selector mechanism of 40 this invention is generally indicated at 20 in Figure 1. The pistol 20 includes as its main element a muzzle 21, a receiver 22, a reciprocal slide 23, a base 24, and a hand grip 25.

The slide 23 is best shown in Figures 3 to 6, 12 and 13.

45 The internal structure of the slide, together with the means for positioning the recoil springs is shown in Figures 7, 8 and 9. As shown in Figures 12 and 13, the slide 23 is machined or otherwise constructed of a single piece of material and has grooves at its bottom designated at 31 and 32. These grooves fit over tracks 34 on either side of the base of the pistol as shown in Figures 3 and 10. The underneath side of the tracks 34 are bounded by grooves 35 upon which bottom lugs 36 and 37 of the slide can ride.

50 55 At the top of the slide and at the rear end is a sight 41. Two extractors 42 and 43 are situated on either side of the forward end of the slide in a longitudinal groove cut therein. Pivot pins 44 and 45 hold the front ends of these extractor pins in place in a normally biased relation to

60 65 the center of the slide through the force of springs 46 and 47 as best shown in Figure 11. Extractor prongs 48 and 49 are beveled on their interior side so that as the slide is pushed forwardly to the position shown in Figure 1, they are spread apart against the force of the biasing spring by the interior walls of grooves 51 located on either side of the breech.

The slide 23 is further provided with a central bore 53 which has a reduced portion 54 at its forward ends opening into an enlarged portion 55 at the front which 70 abuts against the base of a cartridge when the slide is forward. Situated within the bore 53 is a firing pin 56 biased to the rear by a spring 57. To the rear of the

firing pin a hammer 58 is situated in a recess 59 of the base. A magazine opening 60 is likewise provided in the base which extends down into the stock 25 for the insertion of a cartridge clip with the cartridges in the usual manner.

As best shown in Figure 6, the receiver 22 is secured to the base 24 at the front by a lug nut 61 and at the rear by a lug nut 62. The receiver 22 is provided with a shouldered opening 63 at the rear to receive a nut 64 for securing a stop block 65 thereto. A plate 66 is secured to the stop block and to the receiver 22 as shown in Figure 6 and has a tongue 67 and a groove 68 at either side so as to receive the grooves 31 and 32 and the lugs 36 and 37 on the slide as it reciprocates. This tongue and groove arrangement for the plate 66 is best shown in Figures 7 and 9.

The recoil spring structure is best shown in Figures 6 to 10. As shown in Figures 6 and 7 the slide 23 is solid at its forward portion, but is hollowed out at the rear to provide a space 70 as shown in Figure 6. This permits the hammer 58 to operate. In the forward position there are two bore holes 71 and 72, respectively, which are stopped in the front by stop nuts 73 and 74. Situated in the holes are recoil springs 75 and 76 while guide plungers 77 and 78 keep these springs in a straight position. It will be noted that the springs through their guide plungers are adapted to abut at their rear end against the stop block 65 as shown in Figure 7 when the slide 23 is in the forward position.

In order to provide for a cutting out of operation of the spring 76 a selector switch 80 is provided. This switch provides for a cut-out of the single spring 76 while the other spring 75 is in operation at all times. The selector switch 80 is mounted on the top of the slide 23 as shown in Figure 2 upon a pivot pin 81 which extends down through the top of the slide as shown in Figure 6, and is fixed at its bottom to a cut-out cam 82. This selector switch, when turned to the position indicated in Figure 9, is adapted to cut out the spring 76 and keep it from striking the stop block 65. This reduces the effective recoil spring force when light cartridge loads are utilized. The selector switch is shown in full detail in Figures 14 through 16 and includes a spacing collar 83 between the selector cam 82 and the switch 80.

Operation

First of all, the operation will be described where a heavily loaded cartridge is employed. By such operation, the selector switch position will be that shown in full lines in Figure 2. Thus, the cam 82 will be in the position shown in Figure 7, i. e., the cut-in position where the recoil spring 76 is free to operate.

The pistol is loaded in the usual manner and the slide 23 is pushed to its forward position. In this state, the extractors 42 and 43 are spread slightly apart in the extractor grooves 51. When the pistol is fired, the natural repulsive force acts against the slide 23 and propels it to the rear and the extractors 42 and 43 are permitted to close inwardly and extract the cartridge from the breech. Then, by the usual ejection means (not shown) the cartridge is ejected. The slide 23 is repelled toward the stop block 65 as the guide plungers 78 and 77 are positioned thereagainst while the two recoil springs 75 and 76 cushion the shock from the exploded cartridge.

The hammer 58 in the firing operation strikes against the firing pin 56 in the usual manner to explode the cartridge, and when the slide is propelled to the rear, the hammer is automatically recocked in the standard manner of operation for semiautomatic firearms. When the slide 23 is returned to the forward position, a new cartridge from the cartridge clip in the magazine (not shown) is picked up by the front of the slide and positioned in the breech. This completes the operation.

Where a cartridge having a light explosive charge, such as a .22 short is utilized, it is desirable that the

recoil spring load be less than where a higher explosive charge is employed, such as by a .22 long. In such a case, the recoil spring 76 is desired to be placed in the cut-out position, so that it will not resist the rearward movement of the slide. This is effected, first of all, by manually moving the slide to the rear as shown in Figure 8, and then moving the selector switch 80 to the position shown in dotted lines in Figure 2. This will present the cam 82 directly behind the guide plunger 78 as a stop so that the spring 76 will not abut against the slide block 65 when the slide is moved forward. This condition is shown in Figure 9 where the slide has been pushed forward and is ready for operation with a .22 short. The firing operation then is the same as above described, with the obvious exception that only the spring 75 is presented as a recoil spring, since it is the only one now in operative condition against the stop block.

Various changes and modifications may be made in this invention for the employment of the selector recoil mechanism for use in various firearms. As an example, more than two recoil springs can be utilized with selective control means for all except the standard spring. Such changes and modifications will be apparent to those skilled in the art and are intended to be within the scope of this invention as defined by the claims appended hereto.

What is claimed is:

1. In a firearm of the type described, a reciprocal slide movable to a forward and a rearward position on said firearm, said slide being adapted to be moved to the rearward position by recoil force when the firearm is fired, recoil biasing means urging said slide to the forward position, said recoil biasing means including a multiplicity of recoil biasing members, and selector means for varying the effective force of said recoil biasing means by separately disengaging a part of said recoil biasing members.

2. In a firearm of the type described, a reciprocal slide movable to a forward and a rearward position on said firearm, said slide being adapted to be moved to the rearward position by recoil force when the firearm is fired, recoil biasing means urging said slide to the forward position, said recoil biasing means including a multiplicity of recoil biasing member, and selector means for varying the effective force of said recoil biasing means by separately disengaging a part of said recoil biasing members, said selector means including a manually operable lever on the outside of the firearm.

3. In a firearm of the type described, a reciprocal slide movable to a forward and a rearward position on said firearm, said slide being adapted to be moved to the rearward position by recoil force when the firearm is fired, recoil spring biasing means urging said slide to the forward position, said recoil biasing means including a multiplicity of recoil biasing members, and selector means cooperating with said spring biasing means and adapted to render inoperative at least a part of said spring biasing means by separately disengaging a part of said recoil biasing members.

4. In a firearm of the type described, a reciprocal slide movable to a forward and a rearward position on said firearm, said slide being adapted to be moved to the rearward position by recoil force when the firearm is fired, recoil spring biasing means urging said slide to the forward position, said recoil biasing means including a multiplicity of recoil biasing members, and selector means manually movable between a first and second position, said selector means cooperating with said spring biasing means and adapted to cut in all of the spring biasing means in the first position when a cartridge having a high explosive charge is utilized, and to cut out a part of said spring biasing means in the second position when a cartridge of low explosive charge is employed by separately disengaging a part of said recoil biasing members.

5. In a firearm of the type described, a reciprocal slide

movable to a forward and a rearward position on said firearm, said slide being adapted to be moved to the rearward position by recoil force when the firearm is fired, recoil spring biasing means urging said slide to the forward position, said recoil biasing means including a multiplicity of recoil biasing members and selector means manually movable between a first and second position, said selector means cooperating with said spring biasing means and adapted to cut in all of the spring biasing means in the first position when a cartridge having a high explosive charge is utilized, and to cut out a part of said spring biasing means in the second position when a cartridge of low explosive charge is employed by separately disengaging a part of said recoil biasing members, said selector means including a manually operable lever on the outside of the firearm.

6. In a firearm of the type described, a reciprocal slide movable to a forward position against the breech of the firearm in a closed position and movable rearwardly against a stationary stop on the firearm in an open position, said slide being adapted to be moved rearwardly by recoil force when the weapon is fired, recoil spring biasing means resisting said rearward movement of the slide, said recoil biasing means including a multiplicity of recoil biasing members, selector means manually movable between a first and second position for controlling the effective force of said recoil spring biasing means by separately disengaging a part of said recoil biasing members, said selector means adapted to actuate a high recoil spring force in the first position when a cartridge having a high explosive charge is utilized and a low recoil spring force in the second position when a cartridge having a low explosive charge is employed.

7. In a firearm of the type described, a reciprocal slide movable to a forward position against the breech of the firearm in a closed position and movable rearwardly against a stationary stop on the firearm in an open position, said slide being adapted to be moved rearwardly by recoil force when the weapon is fired, recoil spring biasing means resisting said rearward movement of the slide, said recoil biasing means including a multiplicity of recoil biasing members, selector means manually movable between a first and second position for controlling the effective force of said recoil spring biasing means by separately disengaging a part of said recoil biasing members, said selector means adapted to actuate a high recoil spring force in the first position when a cartridge having a high explosive charge is utilized and a low recoil spring force in the second position when a cartridge having a low explosive charge is employed, said selector means including a manually operable lever on the outside of the firearm.

8. In a firearm of the type described, a reciprocal slide movable to a forward position against the breech of the firearm in a closed position and movable rearwardly against a stationary stop on the firearm in an open position, said slide being adapted to be moved rearwardly by recoil force when the weapon is fired, recoil spring biasing means resisting said rearward movement of the slide, selector means for controlling the effective force of said recoil spring biasing means, said spring biasing means including at least two compression springs mounted in said slide adapted to have one end abut against said stop, and said selector means adapted to remove at least one of said compression springs from its abutting relation against the stop means for rendering the biasing force therefrom ineffective.

9. In a firearm of the type described, a reciprocal slide movable to a forward position against the breech of the firearm in a closed position and movable rearwardly against a stationary stop on the firearm in an open position, said slide being adapted to be moved rearwardly by recoil force when the weapon is fired, recoil spring biasing means resisting said rearward movement of the slide, selector means for controlling the effective force

of said recoil spring biasing means, said spring biasing means including at least two compression springs mounted in said slide adapted to have one end abut against said stop, and said selector means adapted to remove at least one of said compression springs from its abutting relation against the stop means for rendering the biasing force therefrom ineffective, said selector means including a manually operable lever mounted on the outside of said slide.

10. In a firearm of the type described, a reciprocal slide movable to a forward position against the breech of the firearm in a closed position and movable rearwardly against a stationary stop on the firearm in an open position, said slide being adapted to be moved rearwardly by recoil force when the weapon is fired, recoil spring biasing means resisting said rearward movement of the slide, selector means manually movable between a first and second position for controlling the effective force of said recoil spring biasing means, said spring biasing means including at least two compression springs mounted in said slide adapted to have one end abut against said stop, and said selector means adapted to actuate a high recoil spring force in the first position when a cartridge having a high explosive charge is utilized, and a low recoil spring force in the second position when a cartridge having a low explosive charge is employed, said selector means adapted to remove at least one of said compression springs from its abutting relation against the stop means for rendering the biasing force therefrom ineffective, said selector means including a manually operable lever mounted on the outside of said slide.

11. In a firearm of the type described, a reciprocal slide movable to a forward position against the breech of the firearm in a closed position and movable rearwardly against a stationary stop on the firearm in an open position, said slide being adapted to be moved rearwardly by recoil force when the weapon is fired, recoil spring biasing means resisting said rearward movement of the slide, selector means manually movable between a first and second position for controlling the effective force of said recoil spring biasing means, said spring biasing means including at least two compression springs mounted in said slide adapted to have one end abut against said stop, and said selector means adapted to actuate a high recoil spring force in the first position when a cartridge having a high explosive charge is utilized, and a low recoil spring force in the second position when a cartridge having a low explosive charge is employed, said selector means adapted to remove at least one of said compression springs from its abutting relation against the stop means for rendering the biasing force therefrom ineffective, said selector means including a manually operable lever mounted on the outside of said slide, said lever including a cam on the interior of said slide which is adapted to act as an abutment for the end of the compression spring which is to be rendered ineffective and to keep said end abutting against said stationary stop on the firearm.

12. In a firearm of the type described, a reciprocal slide movable to a forward position against the breech of the firearm in a closed position and movable rearwardly against a stationary stop on the firearm in an open position, said slide being adapted to be moved rearwardly by recoil force when the weapon is fired, recoil spring biasing means resisting said rearward movement of the slide, selector means manually movable between a first and second position for controlling the effective force of said recoil spring biasing means, said spring biasing means including at least two compression springs mounted in said slide adapted to have one end abut against said stop, and said selector means adapted to actuate a high recoil spring force in the first position when a cartridge having a high explosive charge is utilized, and a low recoil spring force in the second position when a cartridge having a low explosive charge is employed, said selector

means adapted to remove at least one of said compression springs from its abutting relation against the stop means for rendering the biasing force therefrom ineffective, said selector means including a manually operable lever mounted on the outside of said slide, said lever including a cam on the interior of said slide which is adapted to act as an abutment for the end of the compression spring which is to be rendered ineffective and to keep said end abutting against said stationary stop on the firearm, said cam being adapted to be moved by said slide to the rear of said stop when the slide is moved to

the rear for disengaging the end of the compression spring to be rendered ineffective from the stop when said slide is again moved forwardly.
